ABSTRACT

A tensioning apparatus that includes a housing through which a threadline passes in a straight path. The housing contains a plurality of rings suspendable from the threadline and maintains these rings for free movement in a plane oriented at tilt and skew angles with respect to the threadline of from about 5° to about 45°.

RING AND BAR TENSIONER

BACKGROUND OF THE INVENTION

This invention concerns a tensioning device and more particularly a device of the ring and bar type for maintaining a uniform tension on moving yarns. The device is particularly suitable for use in high speed textile operations such as yarn beaming. Yarn tensioning devices are known which consist of a series of horizontal, parallel guide pins across which the yarn passes and rings suspended by the yarn hanging between the pins. The number and weight of the rings suspended by the yarn determines the yarn tension delivered. Such known devices are suitable for controlling tension on yarns moving at relatively low speeds, such as on knitting machines. On yarns moving at high speeds from a supply package which tends to deliver the yarn under variable tension, such devices are found to give inadequate tension control due to vibration or chattering of the rings caused by tension variations in the feed yarn. In addition the rings are subject to wear at substantially only one area on the yarn contact surface.

Accordingly, an object of this invention is a tension device of the alternating suspended ring and bar type which provides tension control suitable for use in high speed yarn beaming operations. Other objects are a tensioning device which provides positive control and containment of the yarn at all times while running and during stops and starts, longer life and ease of changing from one tension level to another.

SUMMARY OF THE INVENTION

The invention is a yarn tensioning device comprised of two opposed vertical end means with circular yarn guide means defining a yarn path therebetween; said end means connected by two opposing vertical parallel sides; a plurality of parallel yarn guide pins connecting said sides, said pins defining a plane substantially adjacent to and parallel with said yarn path; said guide pins interspersed with a plurality of parallel rings suspendable from a yarn passing through said device; the planes of said rings being maintained substantially parallel to the axes of said guide pins, but said planes being tilted by an angle of from about 5° to 45° from a vertical line perpendicular to said threadline path by opposing straight channels in said sides between said guide pins.

Another embodiment is the above device wherein the axes of said pins and said ring planes are skewed at an angle of from about 5° to 45° with respect to a horizontal line perpendicular to said yarn path.

In a preferred embodiment, the planes of the rings in said device are maintained by said channels at a tilt angle of from about 10° to 30° and a skew angle of from 5° to 15° as described.

BRIEF DESCRIPTION OF THE DRAWING

FIG. 1 is a top view of a tensioning device of this invention.
FIG. 2 is a side view of the same device.

DETAILED DESCRIPTION OF THE PREFERRED EMBODIMENT

Referring now to FIG. 1, a housing 10 is formed from integral side and end pieces 11 and 12 joined at each end to support circular yarn inlet guide 13 and outlet guide 14 which define the yarn path 15 through the device. Sides 11 and 12 are connected by and provide support for parallel guide pins 16. Sides 11 and 12 contain inwardly facing straight channels 18, the channels on opposing sides being displaced such that the planes of tensioning rings 17 are skewed by angle *a* with respect to a horizontal line perpendicular to yarn path 15. A mounting bracket 20 supports housing 10.

FIG. 2 shows side 12 having channels 18 on its inside surface, said channels being tilted in the direction of movement in yarn path 15 by an angle *b* with respect to a line perpendicular to yarn path 15. The channels 18 are interspersed by guide pins 16. A movable ring keeper pin 19 is supported by the

ends of the device. The ring keeper pin 19 serves as a rest for rings in channels 18 when in an inactive raised position.

The essential and novel feature of this invention is the use of channels in the sides of the tensioner to substantially contain free movement of the rings in all but a sloped vertical direction. The use of such channels to maintain the planes of the rings at an angle tilted from about 5° to 45°, preferably 5° to 30°, with respect to a line vertical to the yarn path results in a reduction of ring chatter at high yarn speeds; such chatter being caused by variations in tension of the feed yarn. Reduction or elimination of such chatter results in more uniform tension control.

Placement of the channels so as to orient the planes of the rings at a skew angle of 5° to 45°, preferably 5° to 15°, with respect to a horizontal line perpendicular to the yarn path results in rotation of the rings during use such that localized wear on the yarn contact surface of the rings is eliminated leading to longer ring life.

The particular tilt and skew angles necessary for desired operation is dependent in each case upon the uniformity of tension on the feed yarn, frictional coefficient of the tensioner body material with the ring material in the channels, frictional coefficient between the rings and the particular yarn and clearance between the channels and the rings.

In use, the tension device of this invention preferably is oriented with respect to yarn travel such that the plane of the rings is tilted from a vertical position, in the direction of yarn travel, that is, the tops of the channels are displaced with respect to the bottom end thereof in the direction that the yarn is moving.

The device may be constructed of any suitable materials. The yarn contacting surfaces (end guides, guide pins, rings) are preferably constructed of, or at least coated with, known ceramic materials for long wear. The end and channeled side pieces are conveniently constructed of durable plastic materials such as general purpose polystyrene. Where desired, dampening or elimination of ring chatter during operation can be realized through the use of a rubber or rubber-like material with a high coefficient of friction for the tensioner body. For example, a 50 Shore A hardness rubber body gives significantly more dampening than a methylmethacrylate body.

Yarn tension control and confinement is maintained by threading the yarn through the eyelets and rings above the guide pins. The number and weight of rings employed will determine the tension level attained. Preferably the device contains at least two rings and at least three guide pins. Any number of rings and bars to attain the tension and control desired may be employed. The rings may have a circular or polygonal cross-section although a circular yarn contacting inner surface is preferred.

Control of the yarn during stoppage is maintained by the rings dropping lower between the bars thereby increasing yarn frictional drag as the angle of wrap is increased around the rings and bars. Since vertically oriented rings tend to drop and brake the yarn more quickly than the tilted rings when the yarn is stopped, the apparatus may include a minor number of vertically oriented rings, in addition to the tilted rings, when faster braking of the yarn is desired to avoid slack in the stopped yarn. Since the yarn is contained within the rings, there is no chance for yarn to become unthreaded.

All the rings in a device do not need to be employed during use. They can be held out of action in a known manner by the use of a movable keeper pin or bar 19 inserted between the ends such that the rings are held up out of contact with the yarn. The ring keeper can be inserted such that the yarn passes through the rings while they are being held above the yarn but remain in a threaded position ready for action as needed.

Although the illustrated embodiment shows the rings and bars alternately spaced throughout the device. This spacing is not essential for effective operation. For example, if the rings at each end of the housing 10 are the only rings actively engaging the yarn then every other guide bar between the rings could be removed without affecting operation and there are other similar spacing relationships that may be employed.

A tension device of the type shown in the figures, having a ring tilt angle of 25° and a skew angle of 10° as defined herein, provided tension control of 3.5 ± 0.1 grams during the beaming of 30 denier, 10-filament nylon yarns at 600 ypm. using three one gram rings and of 5.0 ± 1.5 grams during the beaming of 70 denier, 34-filament nylon yarn at 600 ypm., using four 1 gram rings.

What is claimed is:

1. A threadline tensioning apparatus including; a housing formed of parallel ends joined to each other by opposed parallel sides said ends having guide means for passing a threadline therethrough in a straight path; a plurality of guide pins connected between said sides below said path; a plurality of rings positioned in said housing in a spaced relationship to each other and suspensible from a threadline passing through the housing; the improvement comprising; a plurality of pairs of opposed inwardly facing channels in said sides, each pair maintaining therebetween a ring for free movement in a plane with respect to the threadline, said plane being at a tilt angle of from about 5° to about 45° from a vertical line perpendicular to said path, said plane being skewed at an angle of from

about 5° to about 45° with respect to a horizontal line perpendicular to said path.

2. The apparatus as defined in claim 1 said tilt angle being from about 10° to about 30°, said plane being skewed at an angle of from about 5° to about 15°.

3. A threadline tensioning apparatus including; a housing formed of parallel ends joined to each other by opposed parallel sides, said ends having guide means for passing a threadline therethrough in a straight path; a plurality of guide pins connected between said sides below said path; a plurality of rings positioned in said housing in a spaced relationship to each other and suspensible from a threadline passing through the housing; the improvement comprising; a plurality of pairs of opposed inwardly facing channels in said sides, each pair maintaining therebetween a ring for free movement in a plane with respect to the threadline, said plane being skewed at an angle of from about 5° to about 45° with respect to a horizontal line perpendicular to said path.

4. The apparatus as defined in claim 3, said plane being skewed at an angle of from about 5° to about 15°.
